UNITED STATES PATENT OFFICE.

FRED A. READ, OF LYNN, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-STITCHING MACHINE.

1,140,482.

Specification of Letters Patent. Patented May 25, 1915.

Application filed May 23, 1913. Serial No. 769,375.

To all whom it may concern:

Be it known that I, FRED A. READ, a citizen of the United States, residing at Lynn, in the county of Essex and State of Massachusetts, have invented certain new and useful Improvements in Buttonhole-Stitching Machines, of which the following is a specification, reference being had therein to the accompanying drawing.

10 This invention relates to buttonhole stitching machines, more particularly machines of that type which is known to the trade as the "Reece" button hole machine, wherein a stitch frame carrying the stitch forming mechanism on the one hand and a work clamp or support on the other hand, is relatively movable so as to enable the stitching to be carried along the sides of the buttonhole and around its end or ends.

15 20 Such stitch forming mechanism comprises usually an eye-pointed needle carrying the upper thread and, below and opposed thereto, the so-called "complemental stitch forming mechanism" or "under-sewing mechanism", which carries and operates an under thread in coöperation with the needle carrying the upper thread.

Reference may be made for convenience to the prior patent of W. W. Dixon, No. 30 695,039, as illustrating the general type of buttonhole stitching machine to which the present invention is shown applied.

It is a general object hereof to simplify the construction and operation of machines 35 of the class referred to.

A particular object hereof is to improve the fittings of the curved under needle which oscillates along a curved path from below to above the work, by providing such needle 40 with a needle carrier having a spoke and a hub, the carrier spoke and hub combined into a single rigid member, and having a bearing engaged by the hub, and located wholly beneath the work support in a fixed 45 position upon the bodily shifting stock, which carries the under sewing mechanism.

Thus the objectionable curved race of the aforesaid Patent 695,039 is dispensed with, and at the same time no loose connections or 50 links have been introduced in lieu thereof.

Another object is to provide a special construction of bearing for the needle's circular movements, which will enable the needle's center of oscillation to be located

substantially at, although slightly below, the 55 work level, thus insuring that the needle will enter the plane of the work at substantially right angles thereto; this being attained by the use of an opposed-cone or point bearing, which may be located in a 60 very high position beneath the work support, and yet capable of movement thereunder with the shifting of the stock.

Another object is to provide a special adjustability of the opposed-point bearing by 65 fitting one of the opposed points to adjust transversely to the axis of the needle's swinging, whereby the adjuster may initially properly adjust the position of the needle's path; while the other point is adjustable axially for securing suitable relation to the hub.

Another object is to provide in an under sewing mechanism, having the combined carrier, spoke and hub referred to, a means of 75 relative adjustment as between the carrier and hub; this being effected by increasing or decreasing the length of the connecting spoke thereby altering as desired the needle's radius of oscillation.

Still further objects will be made to appear in the hereinafter following description.

First will be described for convenience, one form in which the present invention may 85 be embodied, and thereafter the novel features will be set forth in the appended claims.

In the accompanying drawings forming a part hereof, Figure 1 is what will be 90 termed a front elevation of a buttonhole sewing machine of the type hereinbefore referred to, and embodying the present improvements, certain parts being broken away, and others shown in section for better disclosure of the interior. Fig. 2 is a top plan view of the shifting or oscillating stock seen in Fig. 1, together with the under sewing mechanism carried by it. Fig. 3 is a partial right hand side elevation of the 100 machine indicated in Fig. 1. Fig. 4 is a rear elevation of the oscillating stock and mechanism carried by it. Fig. 5 is a right hand elevation of the upper portion of the mechanism. Fig. 6 is a partial front elevation on an enlarged scale showing certain details of Fig. 1. Fig. 7 is a vertical section taken upon the plane 7, 7, of Fig. 6.

Fig. 8 is a detail section taken on the plane 8, 8, of Fig. 7.

Similar reference characters will be employed to designate corresponding parts in the several figures of the drawings.

Certain parts may be referred to only generally, because shown in said prior Patent 695,039.

Above the clamp frame 1, is the overhanging casing 2, in which reciprocates the needle bar 3, eccentrically carrying the eye-pointed upper needle 4. The needle bar and casing may be mounted in a stitch frame not shown, and the stitch frame also carries the curb 5, so that the upper and under sewing mechanism both travel with the stitch frame relatively to the clamp frame 1, as the stitching progresses. For guidance, the curb 5, has bolts 6, bearing against ways 7, under the clamp frame. A rod 8, which derives motion from devices in the stitch frame, effects certain actions to be described.

Above the clamp frame is the cutter 9, with its carrying lever 10. Below the clamp frame, and traveling with the stitch frame, is the stock or block 14, having its circular upper bearing end 15, and near its lower end a gear 16 and a sleeve 17. The sleeve, which is hollow, is integral with the stock, and the hub 23 of the gear 16 surrounds the sleeve, while a nut 24 secures the gear rigidly with the sleeve and stock. Carried by the stock 14 are, the tension 18 for the under thread, the looper 19, and the throat plate 20. Surrounding the circular upper end 15 of the stock 14, is the circular portion 21 of the curb or casing 5, and depending therefrom is a loop shaped portion 22, having a vertical circular opening in its central lower portion, to receive the hollow hub 23 of the gear 16. Within the sleeve 17, is the bar or actuator 25, which is also hollow, to permit the under thread passing upwardly through its lower end and from an aperture 26 thereof to the tension 18.

The actuator 25 effects the movements of the various parts carried by the stock 14, and the actuator is moved upwardly and downwardly through an enlargement 27 at its lower end embraced between two loose cup shaped disks 28 and 29, which are borne respectively upon the two forks 30 and 31 of an oscillating lever 32, pivoted at 33, between two hangers 34, which are connected by screws 35 with the loop shaped portion 22. The extremity of lever 32, is connected to the rod 8 before referred to, whereby the rod can oscillate the lever and thereby vertically reciprocate the actuator 25.

It will be understood that the stock 14 is in the nature of a carriage or frame for supporting the working parts of the under mechanism, and that it shifts bodily during stitching; for example, by a circular movement about its vertical axis, together with

the working parts carried by it, while these parts themselves may be moving as required for forming stitches.

A convenient thread takeup comprises a three armed lever 36, 37, 38, pivoted at 39, 70 the long arm 36 having at its extremity a thread eye, the arm 37 having a spring 40 for turning the lever leftwise in Fig. 1, and the arm 38 coöoperating with a pin 41 on the actuator 25 for swinging the lever. An adjustable stop 42 determines the upward limit of movement of the arm 38, thereby controlling the amount of oscillation of the takeup lever.

The looper 19 has a composite motion as usual. The looper is elongated and hook shaped at its end, with a barb at the point of the hook for entering a loop of upper thread and spreading it for the entrance of the under needle. It is shown fitted for bodily oscillation lengthwise of itself, and for swinging slightly at its operative end laterally to its length. Its preferred action is to move leftwise in Fig. 1, while the upper needle is below the work so as to pass between the needle and upper thread thus taking a loop which it slightly opens or spreads and carries leftwise beyond the path of the under needle, then swinging forward slightly to bring its loop in the path of the under needle which on the following ascent enters the loop, the looper finally withdrawing to the right thus disengaging itself from the loop and taking a proper position to repeat operations.

The train of mechanism for longitudinally bodily oscillating the looper 19 and its carrier 60 comprises the cam lever 61 driven by the pin 62 at the upper end of the actuator 25. The looper carrier and cam lever are connected by a swivel shaft 63 that permits the lateral swinging movement. The train of mechanism for causing such lateral movement comprises a rearwardly extending pin 64, which runs along a curved 110 rock arm 65, Fig. 4, that is carried at the top end of a rock shaft 66 which has a stud and roller 67 at its lower end acted upon by the inclined surfaces of cam arm 68 which is pivoted to the stock 14 at 69 and is actuated to swing upwardly and downwardly through a block 70 centrally engaged by a stud 71 which is secured at its inner end to the actuator 25; and the block and stud 70, 71 may have eccentric adjustability as indicated. A spring 72 is shown tending to hold the pin 64 in contact with the rock arm 65. By these mechanisms the looper 19 is made to properly coöperate with the needles in producing the buttonhole stitch.

The clamp frame 1 with its horizontal plate 99, constitute a work support which may be referred to as a horizontal work support for facility of description, although it will be understood that the use

of such words as "horizontal," "vertical," "upper," "lower," is only in a relative sense. The bodily shiftable stock 14 below the work support has been already referred to, as well as the means for shifting it circularly during stitching operation. The curved under needle 11 is usually curved to the arc of a circle. This needle is adapted to be oscillated along a curved path for forming stitches, usually about a center coincident with its own center of curvature.

The under needle 11 is shown secured to a needle carrier 100, which may be similarly curved. Combined into a single rigid member with the carrier 100, are the spoke 101 and hub 102. These parts may take any forms, the hub constituting a central part adapted to turn on suitable bearings, and the spoke consisting of any rigid connection from the hub to the carrier. During operation there is no relative movement between these three combined parts, although for purposes to appear, it is preferred to constitute the spoke and carrier of different pieces of metal.

It will be noticed that the carrier 100 does not slide in a curved race as in said prior patent, and, therefore, has no tendency to bind and excessively wear, but on the contrary freely swings about its center of oscillation by reason of the hub and spoke arrangement described.

A bearing is provided which is engaged by the hub 102, and is located wholly beneath the work support 99, and in a fixed position upon the stock 14, thereby the stock may freely move beneath the work support, carrying the under needle and fittings with it, without conflict.

Before describing the hub bearing, the actuating connections for the needle carrier will be referred to.

From the upstanding projection 103 of the carrier 100, projects rearwardly an extension or pin 104, which at its rear end Fig. 4, is connected by a short link 105, with the upwardly extending arm 106 of an oscillating lever 107 actuated to swing upwardly and downwardly about its pivot 108, by means of a pin 109 rearwardly projecting from the actuator 25. As is usual, the plane of the needle movement may be slightly inclined from the vertical, and the pivot 108 of the lever 107 will be correspondingly inclined from the horizontal. To allow for relative movements, the horizontal portions of the lever 107 may have a cylindrical recess occupied by a cylinder 110 to which the pin 109 is connected. This affords a universal connection between the actuator 25 and the lever 107. An extension on the swinging end of lever 107 may pass beneath an upright plate 111 for guidance of the extension.

At its upper right hand portion, the stock

14 may be formed or provided with an upstanding extension 112 which is in the nature of a frame or skeleton, it having an elongated and curved opening 113 for the free passage of the pin 104 before referred to.

As an assistance to the hub bearing in guiding the needle carrier, and to protect such bearing from excessive strain, the carrier 100 at its rear side may have a sliding 75 surface contact as shown against the front surface of the extension 112. This sliding contact assists in keeping the needle carrier in its proper path while the pivotal fittings of the hub 102 determine its path.

The hub 102 is shown as fitted to the extension 112 by an opposed-cone or point bearing. Preferably the hub has axial recesses 114 engaged by a front cone 115, and an opposed rear cone 116. The rear cone 85 116 is shown secured to the upstanding extension 112. For supporting the front cone 115 the extension is provided with a bridge piece 117 which may be in the nature of a frame secured in fixed position, spaced 90 apart in front of the extension and opposed to it.

Owing to the compactness of the bearing described, it is possible with this construction to locate the axis about which the 95 under needle swings at an extremely high point almost to the level of the work plate, so that the needle by simple oscillation about a single actual center or hub may effectually pass through the work and return, entering the work plate at nearly right angles to the plane thereof.

A valuable feature of perfection of the above described apparatus is the adjustability of the hub bearings. Thus referring 105 to Figs. 6, 7 and 8, it will be seen that the foremost of the opposed cones or points is adjustable transversely to the axis of the needle's swinging. Thus when being initially adjusted, the mechanism permits the 110 needle's path to be accurately positioned with respect to the throat plate. The cone point 115 is at the inward end of a small casting or support 118 which is shaped to overlie both edges of the upper bar of the bridge 115 piece 117. The bridge piece at this point is formed with a recess 119 at its upper side, and the cone point support 118 fits loosely therein, so as to permit lateral shifting. A bolt 120 passing through parts 118 and 117 120 serves to lock them when in properly adjusted position. As seen in Fig. 8, the bolt 120 engages the part 118 through an elongated slot in the latter so as not to interfere with the lateral shifting or adjustment 125 referred to. The other cone point 116 is formed at the forward end of the screw 121 which has threaded engagement with the extension 112. In this way the rear cone point has axial adjustment for securing a 130

suitable relation between the cone points and the hub. A lock nut 122 secures the screw 121 in adjusted position. In this way one of the cone points adjusts axially for properly setting the bearing, and the other adjusts transversely for properly positioning the needle's path. Reference has already been made to the inclined plane of the needle's movement. This necessitates an axis of swinging which is inclined from the horizontal as is indicated in Figs. 5 and 7. One of the cone points is thereby higher than the other. In the improved arrangement shown, the front or higher cone point is the one that is transversely adjustable, while the one that is axially adjustable is the lower. This arrangement permits the casting or support 118 for the higher cone point 115 to be designed with a beveled off surface 123 at its upper corner so that on top it is substantially horizontal, thus avoiding a vertical projection, and enabling a higher positioning of the needle's axis of swinging.

In order to adjust the relation between the needle carrier 100 and its hub or center of oscillation 102 for varying the effective length of the spoke, and, therefore, the radius of oscillation, the following devices may be employed: The spoke 101 is shown as screw-threaded at 124 to engage a threaded recess within the carrier 100. By this arrangement the parts constitute a rigid unit when in operation, but when detached, the spoke and carrier may be relatively adjusted by the pitch of one or more threads of screw 124. A very simple construction is as shown in which the hub 102 and the screw threaded spoke 101 together constitute a headed screw, with the head for the hub and the other end engaged with the threaded recess of the carrier.

It will thus be seen that a buttonhole stitching machine has been described which attains the advantages and objects hereinbefore referred to, and other advantages will be apparent to those skilled in the art.

Since many of the features and principles referred to may be employed in various forms, irrespective of changes in other details, no limitation herein is intended, either to specific features or details, excepting as set forth in the appended claims.

What is claimed is:

1. A buttonhole stitching machine including in combination, a work support, a bodily shiftable stock below the work support, means for shifting the stock during stitching operations, a curved needle adapted to be oscillated along a curved path for forming stitches, a combined carrier, spoke and hub constituting a single rigid member when in operation, an upstanding extension provided on said stock against which said carrier has a sliding face contact, and a bearing engaged by said hub located wholly beneath

said work support in a fixed position on said extension; said extension consisting of a frame, and having an elongated opening, and said carrier having an actuating projection movable freely within said opening.

2. A buttonhole stitching machine including in combination, a work support, a bodily shiftable stock below the work support, means for shifting the stock during stitching operations, a curved needle adapted to be oscillated along a curved path for forming stitches, a combined carrier, spoke and hub constituting a single rigid member when in operation, and an opposed-cone bearing between said hub and stock located wholly beneath said work support in a fixed position on said stock.

3. A buttonhole stitching machine including in combination, a work support, a bodily shiftable stock below the work support, means for shifting the stock during stitching operations, a curved needle adapted to be oscillated along a curved path for forming stitches, a combined carrier, spoke and hub constituting a single rigid member when in operation, an upstanding fixed extension provided on said stock against which said carrier in its movements has face bearing at one side, and an opposed-cone bearing between said hub and stock located wholly beneath said work support in a fixed position on said extension; said extension provided with a bridge piece spaced apart from the extension, with said hub and opposed cones between them.

4. A buttonhole stitching machine including in combination, a work support, a bodily shiftable stock below the work support, means for shifting the stock during stitching operations, a curved needle adapted to be oscillated along a curved path for forming stitches, a combined carrier, spoke and hub constituting a single rigid member when in operation, and a bearing between said hub and stock located wholly beneath said work support and comprising a pair of opposed points oppositely engaging the hub, one of said points adjustable transversely to the axis of swinging for positioning the needle's path.

5. A buttonhole stitching machine including in combination, a work support, a bodily shiftable stock below the work support, means for shifting the stock during stitching operations, a curved needle adapted to be oscillated along a curved path for forming stitches, a combined carrier, spoke and hub constituting a single rigid member when in operation, and a bearing between said hub and stock located wholly beneath said work support and comprising a pair of opposed points oppositely engaging the hub, one of said points adjustable transversely to the axis of swinging for positioning the

needle's path, and the other point adjustable axially for securing suitable relation to said hub.

6. A buttonhole stitching machine including in combination, a work support, a bodily shiftable stock below the work support, means for shifting the stock during stitching operations, a curved needle adapted to be oscillated along a curved path for forming stitches, a combined carrier, spoke and hub constituting a single rigid member when in operation, and a bearing between said hub and stock located wholly beneath said work support and comprising a pair of opposed points oppositely engaging the hub, one of said points provided with a shiftable support for rendering it adjustable transversely to the axis of swinging for positioning the needle's path.

20 7. A buttonhole stitching machine including in combination, a work support, a bodily shiftable stock below the work support, means for shifting the stock during stitching operations, a curved needle adapted to be oscillated about an axis slightly inclined from horizontal for forming stitches, a combined carrier, spoke and hub constituting a single rigid member when in operation, and an inclined bearing between said hub and stock located wholly beneath said work support and comprising a pair of opposed points oppositely engaging the hub, the lower of said points adjustable axially and the higher one and its fittings beveled off substantially horizontally on top.

25 8. A buttonhole stitching machine including in combination, a work support, a bodily shiftable stock below the work support, means for shifting the stock during stitching operations, a curved needle adapted to

be oscillated along a curved path for forming stitches, a combined carrier, spoke and hub constituting a single rigid member when in operation, and a bearing engaged by said hub located wholly beneath said work support in a fixed position on said stock; said combined member being constructed for adjustment of the effective length of spoke for varying the needle's radius of oscillation, and said bearing comprising two opposed points, relatively adjustable, and axially engaging said hub.

9. A buttonhole stitching machine including in combination, a work support, a needle adapted to be oscillated in a curved path for forming stitches, a combined carrier, spoke and hub constituting a single rigid member when in operation, and a bearing engaged by said hub located beneath said work support; said combined member constructed for adjustment of effective spoke length by screw engagement between carrier and spoke.

10. A buttonhole stitching machine including in combination, a work support, a needle adapted to be oscillated in a curved path for forming stitches, a combined carrier, spoke and hub constituting a single rigid member when in operation, and a bearing engaged by said hub located beneath said work support; said hub and spoke constituting a headed screw with the head for the hub, and said carrier constructed to engage the screw threads of said spoke.

In testimony whereof I affix my signature in presence of two witnesses.
